UNITED STATES PATENT OFFICE.

JOHN MACLEAN, OF ILFORD, ENGLAND.

PORTABLE ELECTRIC DRILLING-MACHINE.

No. 828,945.

Specification of Letters Patent.

Patented Aug. 21, 1906.

Application filed January 12, 1906. Serial No. 295,787.

To all whom it may concern:

Be it known that I, JOHN MACLEAN, consulting engineer, a subject of the King of Great Britain, residing at 50 Wellwood road, Goodmayes, Ilford, Essex, England, have invented certain new and useful Improvements in Portable Electric Drilling - Machines, of which the following is a specification.

10 This invention relates to portable electric drilling-machines; and it has for its object to provide a powerful electric drill which shall yet be of a comparatively light weight.

15 In order that the invention may be clearly understood, I have hereunto appended five explanatory sheets of drawings, whereon—

Figure 1 is a part elevation and a part longitudinal section of the drill. Fig. 2 is a plan thereof. Fig. 3 is a cross-section on the line 20 X X, Fig. 1. Fig. 4 is a section on the line Y Y. Fig. 5 is a longitudinal section of the armature. Fig. 6 is a view of one end, and Fig. 7 a view of the other end, of the armature. Fig. 8 is a view of the drill end of machine. 25 Fig. 9 is a view of the feed end of machine. Fig. 10 is an end view of the hand-feed. Figs. 11, 12, and 13 are views of brush-gear.

On the drawings the same reference characters wherever repeated indicate the same 30 parts.

In this machine the motor is of special construction, whereby great power with little weight is obtained. The armature of the motor, which is external to the field-magnets 35 round which it revolves, consists, as shown at Figs. 5, 6, and 7, of a thin hollow cylinder, preferably made up of stampings slotted on their inner periphery to receive the armature-coils. These stampings, which are marked *a*, 40 are held in place by two end rings *b* *c*, of aluminium, bolted together by bolts *d*. The end ring *b* is united to an end-plate ring *e* by four or other suitable number of arms *f*, so that the distance between the rings is sufficient to 45 accommodate the ends of the armature-coils. This end-plate ring is fitted to an end plate *g*, of aluminium, which contains the ball-bearing *h* of that end of the armature. The cup *h* of this ball-bearing is extended and provided with teeth constituting a steel pinion *i*, by means of which the motor is geared, as hereinafter explained. The other end ring *c* of the armature is connected similarly by arms *j* to a ring *k*, which accommodates the 50 commutator *l*, which is of the ordinary type. This commutator is of a construction which allows of great lightness and strength and ease with which the armature connections can be made. It consists, preferably, of a number of hard-drawn copper bars or blocks 55 *m*, arranged in a ring and suitably insulated by mica or other insulating material from one another and from the end rings *m'* *m''*. These end rings bind the whole of the bars and are secured together by the screw-pins *n*, the outer periphery of the commutator forming the brush-surface. The bars are dovetailed at both ends, and the end rings being machined to suit this section thereby hold the bars rigidly in place. 60

The armature end ring *k*, into which the commutator fits and is secured, is united to a central ball-bearing boss *p* by arms *p'*. The field-magnet stampings *q* are built up on a central fixed shaft *r*, on which are fixed the 65 several ball-bearing cones and brackets which are required in the complete machine. 70

The motor is preferably geared in two stages which are or may be identical in their arrangement. The armature end-plate pinion *i*, before mentioned, gears with a rawhide pinion *s*, carried on a pin *s'* in a coned bracket *t*, fixed to the central shaft. This rawhide pinion *s* further gears with an internally-toothed ring *u*, carried on an end plate *v*, 75 which runs on ball-bearings *w* on the aforesaid coned bracket, the whole forming a neat, compact, and light reduction-gear. The end plate *v*, containing the internal toothed ring *u*, is fitted to a skeleton cylinder or frame *x*, 80 (of which the ring *u* may form a part,) which just runs clear around the motor-armature and has a ball-bearing end plate *x'* at the end remote from the gear. For small drilling-machines this reduction-gear set is sufficient, but 85 for machines as generally used a second gear set is provided. In this case the end plate *v* has the cup *v'* of its ball-bearing so formed as to serve as a steel pinion *v''*, similarly to the armature ball-cup before described, and this 90 pinion gears with a rawhide pinion *i'*, carried on a pin *i''*, in a coned bracket *t'*, fixed to the shaft *r*. The pins *s'* and *i''*, carrying the pinions *s* and *i'*, are screwed into their respective brackets in such a manner that the rotation 95 of the pinions tends to tighten the pins in the brackets and not slacken them. The pinion *i'* gears with an internally-toothed ring *u'*, secured to an end plate *v''*, screwed on the short cupped-spindle *y*, into which the drill 100 (not shown) may be fitted. The end plate *v''* is secured to a cylinder *x''*, which incloses the 105

110

- whole machine and is provided with suitably placed ventilating-holes x^6 . The end plate v^4 of the cylinder x^5 runs freely on the shaft r . Access to the commutator can be obtained 5 through a hinged door (not shown) in the exterior end plate v^4 . The end plate v^3 has secured to it an eccentric e' , on the side of which works the roller e^2 , fitted to the lever e^3 . This lever is keyed or otherwise secured to a 10 shaft e^4 , giving an oscillating motion thereto. This oscillating motion is transmitted by another lever e^5 , at whose opposite end is fitted a pawl e^6 , which gears in a ratchet-wheel e^7 , secured to the nut F . As this nut has only circular movement, the rotation given to it by 15 the ratchet feeds the drill forward by means of the screw E .
- To enable the drill to be fed forward by hand, a handle H , which is made one with a 20 collar h^1 , fitted to the boss of frame end plate B , is also provided with a pawl h^2 , which gears in the teeth of the ratchet-wheel, secured to the nut F , and thus gives a hand-feed.
- 25 The framework of the machine consists of two aluminium end plates A B , united by three steel rods or tubes C ; C' , and C^2 . The end plate B of the framework carries the switch D , which controls the electric current.
- 30 The shaft r of the central field-magnet is fitted rigidly in this end plate. The end plate A of the framework has a central hardened-steel collar G , fitting over the spindle y , which rotates within it. This collar forms a 35 bearing.
- 35 The brush-gear G' is clearly shown in Figs. 11, 12, and 13. It consists of a rocker, of suitable light material, having two arms 1 and 2 at right angles. Secured to and insulated from 40 these arms are the brush-holders 3 and 4. The brushes 5 are of carbon and are rectangular in shape, being held on the commutator by the levers 6, the pressure being regulated by the springs 7. The rocker is fixed in any 45 desired position to the shaft r by the pin 8.
- The corner drilling arrangement is shown 50 in Figs. 1 and 2. It will be seen that the end plate A is extended to a boss A' , into which are fitted two rods or tubes C' ; C^2 , which run 55 parallel with and are just clear of the machine and unite the one side of the two end plates A B . The other side of the end plates are united by the single rod or tube C , which as will be seen, is so formed as to serve as a 60 handle by means of which the machine may be carried and held. The spindle or socket y in this case has a pinion y' , which gears with an intermediate pinion y^2 , which latter drives a pinion y^3 on a spindle or shaft y^4 , 65 running in ball-bearings in the boss A' , said shaft y^4 having connected therewith in any suitable manner a socket y^5 . Motion is transmitted from the spindle or socket y to the drill by the gear y' y^2 y^3 . In this case the feed may be arranged as shown—i. e., in line

with the drill—by transferring the whole of the feed-gear from the center to the side boring spindle.

The construction of the drill can of course be altered or varied in its details of construction according to the work it is to perform. 70

Having now fully described my invention, what I claim, and desire to secure by Letters Patent, is—

1. A portable electric drill comprising, in 75 combination, a frame, a fixed shaft in the frame, a magnet on the shaft, an armature arranged externally of the magnet, a commutator and an inclosing cylinder or framework work, said cylinder or framework being 80 driven by gear from the armature and being adapted to rotate the drill.

2. A portable electric drill comprising, in combination, a frame, a fixed shaft in the frame, a switch, feeding mechanism, a magnet on the shaft, an armature arranged externally of the magnet, a commutator, a skeleton frame driven by gearing from the armature, an inclosing cylinder or framework driven from the skeleton frame aforesaid, 85 said inclosing cylinder or framework having a socket in which the drill is fitted, the several working parts running in ball-bearings. 90

3. A portable electric drill comprising, in combination, a frame, a fixed shaft in the frame, a magnet on the shaft, an armature arranged externally of the magnet, a commutator, an inclosing cylinder or framework, gear for driving the cylinder from the armature, means connected with the cylinder for 95 rotating the drill, means for feeding the drill forward automatically and also for feeding it by hand. 100

4. A portable electric drill comprising, in combination, a frame, a fixed shaft in the frame, a switch, feeding mechanism, a magnet on the shaft, an armature arranged externally of the magnet, a commutator, a skeleton frame running upon ball-bearings 105 on the shaft, internal teeth on this frame, a gear-wheel gearing with the teeth and with a pinion carried on a sleeve running in ball-bearings on the shaft, said sleeve being connected to the armature, and means connected with the skeleton frame for rotating the drill. 110

5. A portable electric drill comprising, in combination, a frame, a fixed shaft in the frame, a switch, feeding mechanism, a magnet on the shaft, an armature arranged externally of the magnet, a commutator, a skeleton frame having internal teeth thereon, 115 a gear-wheel gearing with said teeth on the one hand and with a pinion connected with the armature on the other hand, a bracket for supporting the gear-wheel an inclosing cylinder fitted on the shaft at one end and connected with a socket adapted to receive the drill at the other end, internal teeth on the inclosing cylinder, a gear-wheel, a pinion 120 running in ball-bearings and connected with 125

130

a skeleton frame, and a bracket for supporting the gear-wheel.

6. A portable electric drill comprising, in combination, a frame, a fixed shaft in the frame, a magnet on the shaft, an armature arranged externally of the magnet, a commutator, an inclosing cylinder, gear connected with the armature for rotating the cylinder, a socket connected with the cylinder, a bracket on the frame, a short shaft with a second socket therein carried by the bracket, teeth on this socket, external teeth on the socket of the inclosing cylinder and an intermediate pinion adapted to engage with said teeth and with the teeth of the second socket.

7. A portable electric drill comprising, in combination, a frame, a fixed shaft in the frame, a magnet on the shaft, an armature

arranged externally of the magnet, a commutator, an inclosing cylinder driven by gear from the armature, a socket connected with the cylinder, teeth on the socket, a bracket on the frame, a shaft having a socket at one end thereof carried by the bracket, teeth on both sockets, an intermediate pinion, a screw for feeding the drill, ratchet mechanism for operating the screw, a second bracket with screw-hole therein which is in line with the second socket and which is adapted to receive a feed-screw.

In testimony whereof I affix my signature in presence of two witnesses.

JOHN MACLEAN.
